UNITED STATES PATENT OFFICE.

EDWARD M. HEYLMAN, OF SOUTH BEND, INDIANA, ASSIGNOR TO OLIVER CHILLED PLOW WORKS, OF SOUTH BEND, INDIANA.

AGRICULTURAL IMPLEMENT.

Original application filed March 14, 1918, Serial No. 222,334. Divided and this application filed September 27, 1918. Serial No. 255,928.

To all whom it may concern:

Be it known that I, EDWARD M. HEYLMAN, a citizen of the United States, and a resident of South Bend, in the county of St. Joseph and State of Indiana, have invented certain new and useful Improvements in Agricultural Implements; and I do hereby declare the following to be a full, clear, and exact description of the invention, such as 10 will enable others skilled in the art to which it appertains to make and use the same.

This invention relates to improvements in agricultural implements, such as plows, and more particularly to mountings for the 15 disks, this application being a division of application for patent filed by me on the 14th day of March 1918 and designated by Serial No. 222,334.

One object of the present invention is to 20 so construct a disk mounting that the part which constitutes the bearing for the disk spindle shall be of such form and proportions that it will be prevented from dragging against the "bank" when plowing 25 deeply.

A further object is to improve the structure and enhance the strength and efficiency of the bearings of a disk plow.

With these and other objects in view, the 30 invention consists in certain novel features of construction and combinations of parts as hereinafter set forth and pointed out in the claim.

In the accompanying drawings; Figure 1 35 is a sectional view showing an embodiment of my invention; Figure 2 is an end view of the flanged spindle; Figure 3 illustrates the washer at one end of the spindle; Figure 4 is a view of the arm or plate having 40 the hub in which the disk spindle is mounted, and Figures 5 and 6 are views of the bushings.

1 represents a soil-engaging disk and 2 a beam or other part of a plow structure 45 with which the disk is connected through the medium of suitable instrumentalities.

A spindle 3 for the disk is provided with an annular flange 4 which is securely fastened to the back of said disk by means of 50 bolts 5. The spindle 3 is mounted in a hub 6 and the latter is connected, through the medium of an arm or plate 7^a (which may be integral with said hub) and attaching devices, with the beam or frame member 2.

The hub 6 is also made with an opening 6^a 55 to permit dirt that may work in from the top and front, to drop out.

The spindle 3 is made large at the portion thereof nearest the flange 4 in order to gain adequate strength at this portion of the spindle, and the rear portion of said spindle is contracted in size so that the rear end of the bearing may be so reduced in size as to prevent the same from dragging 60 against the "bank" in case of deep 65 plowing. The hub 6 has the same general shape as the spindle, and two separate bushings 7, 8, are employed,—the bushing 7 encircling the larger portion of the spindle, and the bushing 8 encircling the smaller 70 portion thereof. These bushings are made with keys 9 to enter suitable key-ways in the hub, and the space between the two bushings forms a lubricant chamber 10, with which a lubricant cup 11 placed upon the top of the hub communicates. The larger bushing 7 bears at one end against a shoulder 12 on the spindle and at the other end it has a thrust bearing against a flange 75 or rib 13 in the hub 6, while the smaller 80 bushing 8 rests at one end against a flange or rib 14 in the hub and at the other end against a cap 15 screwed into the end of the hub. Thus the thrust of the 85 disk coming against the bushing member 7 will be resisted by the rib 13, and displacement of the smaller bushing member 8 will be prevented when the plow is 90 raised, by the rib 14. A bolt 16 passes through the spindle 3 and its inner portion is threaded to enter the threaded portion of the bore in said spindle. The outer end of the bolt 16 is provided with a head 17, between which and the end of the spindle, a washer 18 is located. This washer overlies 95 the bushing member 8 and is provided with lugs 19 which enter sockets 20 in the end of the spindle 3. It will be seen that the bearing parts of the spindle at the bushings are substantially straight, and this is an advantage over a taper construction because, 100 if there is any end play, there will not be too much up-and-down play in the bearing when the spindle is drawn forwardly.

Having fully described my invention what I claim as new and desire to secure by Letters-Patent, is:—

The combination of a supporting member

provided with a hub member having two portions differing in diameter, a soil engaging disk, a spindle having a central bore provided with a threaded portion and having two bearing portions differing in diameter, bushings disposed between the hub and the respective bearing portions of the spindle and separated from each other, forming a chamber between them, said spindle having 10 a part fixed to the rear face of the disk, a bolt in the bore of the spindle and headed at its rear end, said bolt terminating at its other end rearwardly of the disk and engaging the threaded portion of the bore in

the spindle, a disk disposed between the head of the bolt and the free end of the spindle and engaging the latter, and a cap entering said hub and enclosing the free end of the spindle and the headed end of said bolt. 15

In testimony whereof, I have signed this specification in the presence of two subscribing witnesses.

EDWARD M. HEYLMAN.
